UNITED STATES PATENT OFFICE.

ROBERT HUGHES, OF WATERFORD, NEW YORK.

HYDRANT.

SPECIFICATION forming part of Letters Patent No. 394,652, dated December 18, 1888.

Application filed August 7, 1888. Serial No. 282,142. (No model.)

To all whom it may concern:

Be it known that I, ROBERT HUGHES, a citizen of the United States, residing at Waterford, in the county of Saratoga and State of New York, have invented new and useful Improvements in Hydrants, of which the following is a specification.

This invention relates to improvements in hydrants of that class known as "fire-hydrants," and which in operation have a fire-hose connected to their discharge-opening; and it consists in certain novel features hereinafter described and claimed.

In the accompanying drawings, Figure 1 is a vertical section of the stand-pipe or casing of my hydrant, showing the interior mechanism in side elevation. Fig. 2 is a vertical section of the casing, the interior mechanism being removed. Fig. 3 is a horizontal section on the line *x x* of Fig. 1. Fig. 4 is a view similar to Fig. 1, and showing the parts in a different position. Fig. 5 is a rear view of the plunger, and Fig. 6 is a vertical section on the line *y y* of Fig. 7. Fig. 7 is a detail view.

Referring to the drawings by letter, A designates the stand-pipe or casing, of the usual construction, provided with an inlet-opening, B, in one side near its lower end and having a suitable discharge-opening at its upper end. On the upper side of the bottom of the casing I provide a drip-cup, C, having suitable apertures, D, in its side, and having an open bottom which registers with a vertical opening, E, in the bottom of the casing.

F designates my improved plunger, consisting of the plunger-head G, having the disk-valve H secured to its front side and provided on its rear side with the ribs or flanges I J, which are adapted to engage a vertical rib, K, on the rear side of the casing, thereby guiding the plunger vertically in its up-and-down movement. The disk-valve H is provided on its front face with a packing-ring, L, and is adapted to close the inlet-opening B, the packing-ring serving to form a watertight joint with the front side of the casing. The plunger-head is enlarged at its lower end and the flanges I are at the opposite sides or edges of this enlarged portion and are adapted to engage the side edges of an enlargement, M, at the lower end of the rib K at the lower

side of the casing. The flanges J are provided at the upper end of the plunger-head, and the lower edges of said flanges are beveled outwardly and downwardly, so as to engage the upper beveled edges of the enlargement M, and thereby limit the downward movement of the plunger-head.

The disk-valve H is provided on its rear side at its center with a stud, N, which engages a circular opening, O, in the front side of the plunger-head, and is cushioned therein by means of a small rubber block, P, secured in the plunger-head.

Q Q designate triggers, which are arranged in sockets R, formed in the plunger-head, and depend from the lower end of the same, and are adapted in the operation of the device to contact with a block, S, on the bottom of the casing, and thereby be forced upward in the sockets R. The upper ends of the triggers Q are made wedge-shaped and act upon the wedges T, which are seated in recesses U in the front face of the plunger-head and bear against the rear side of the disk-valve H. By this arrangement when the plunger is lowered the wedges T are forced outward, and, bearing against the disk-valve, cause it to bind firmly against the front side of the casing, and thereby effectually cut off the flow of the water.

In order to reduce friction between the wedges T and the triggers Q, I provide between their adjacent surfaces the friction-rollers V.

The plunger is provided with an interior screw-threaded opening, X, which is engaged by the operating screw-shaft Y, as shown.

Z designates a vertical stationary rod provided at its upper end with a laterally-projecting collar, *a*, swiveled on the upper end of the operating-shaft. The said rod lies in a groove, *b*, in the side of the plunger-head and has pivoted to its lower end and at a suitable point above its lower end the link *c* and dog *d*. The dog *d* has its rear end pivoted to the upper end of a piston-rod, *e*, and the rear end of the link *c* is pivoted to the said piston *e*, the said piston *e* having a piston-head, *f*, on its lower end, which is adapted to engage the drip-cup C and prevent the flow of water through the same. The front end of the dog *d* has its upper edge provided with a tongue,

g, and a recess, *h*, in the rear of the said tongue, the front edge of the said dog being beveled downwardly and rearwardly, as shown. The said tongue is adapted to engage a lateral pin, *i*, at the upper end of the plunger-head, and the front beveled end of the dog rides over the curved upper edge of a guide-strip, *j*, formed on the side of the plunger-head and extending nearly the entire length 10 of the same.

The construction and arrangement of the several parts of my hydrant being thus made known, the operation of the same, it is thought, will be readily understood.

15 The normal position of the parts is that shown in Fig. 1, in which position the plunger-head is at the lower end of the casing or stand-pipe, and the inlet-opening is closed by the disk-valve *H*, and the piston *f* is raised 20 from the drip-cup, so that the water which may collect in the stand-pipe may readily escape through the body into the main or tank forming the source of supply. When it is desired to use the device, the operating-shaft 25 is rotated so as to raise the plunger, thereby removing the disk-valve *H* from over the inlet-opening and allowing the water to enter the casing or stand-pipe, through which it will rise to the discharge-opening at the upper end of the same and thence pass out 30 through the hose. As the plunger-head rises, the upper curved end of the guide-plate *j* will impinge against the front beveled end of the dog *d* and raise the said front end of said dog, thereby lowering the rear end of the dog and depressing the piston *e*, so as to drive the piston-head *f* into the drip-cup, closing the same and preventing the flow of the water therethrough, so that the water will be caused 35 to rise positively through the casing or stand-pipe.

When it is desired to cut off the flow of water, the operating-shaft is rotated so as to lower the plunger, thereby moving the valve-disk over the inlet-opening. As the plunger-head descends, the pin *i* on the upper end of the same will engage the tongue *g* of the dog *d*, and thereby lower the front end of the said dog, consequently raising the piston *e* and 40 withdrawing the piston-head *f* from the drip-cup, so that the water in the stand-pipe or casing will be allowed to escape and be prevented from stagnating.

From the foregoing description, taken in connection with the annexed drawings, it will be seen that I have provided a simple and efficient fire-hydrant, and the advantages of the same are thought to be obvious.

Having thus described my invention, what I claim, and desire to secure by Letters Patent, is—

1. In a hydrant, the combination of the casing, the plunger-head moving vertically in

the casing and having in its front side a circular opening, *O*, and the recesses *U*, arranged on opposite sides of said opening, and provided in its bottom with the sockets *R*, the disk-valve having a stud engaging the opening *O*, the wedges seated in the recesses *U* and bearing against the rear side of the disk-valve, and the triggers projecting through the sockets *R* and having wedge-shaped upper ends bearing against the wedges in the recesses *U*, as set forth. 65

2. The combination of the casing, the plunger-head moving vertically in the casing and provided in its front face with the circular opening *O*, and the recesses *U* on opposite sides of said opening, and having the sockets *R* in its bottom, the disk-valve having a stud, *N*, engaging the opening *O*, the cushion *P*, secured in the plunger-head and bearing on said stud, the wedges *V*, seated in the recesses *U* and bearing against the rear side of the disk-valve, the triggers projecting through the sockets *R* and having wedge-shaped upper ends acting on the wedges *V*, and the friction-rollers arranged between the said triggers and wedges, as set forth. 70

3. The combination of the casing having an inlet-opening and provided on the inner face of its rear side with the vertical guide-rib *K*, having an enlargement, *M*, at its lower end, and the vertically-movable plunger carrying a disk-valve adapted to close the inlet-opening 90 and provided on its rear side with the flanges *J* at its upper end, having beveled lower edges adapted to contact with the enlargement *M*, the plunger being further provided at its lower end with the flanges *I*, adapted to engage the edges of the enlargement *M*, as specified. 95

4. The combination of the casing having an inlet-opening and provided with a drip-cup in its bottom, the plunger moving vertically 105 in the casing and carrying a valve adapted to close the inlet-opening, the pin *i*, projecting laterally from the upper end of the plunger, the guide-plate *j* on the side of the same terminating below said pin, the stationary rod, the piston arranged adjacent to the plunger and adapted to close the drip-cup, and the dog pivoted at its center to the stationary rod and at its rear end to the piston, the front end of the dog being arranged in the path of the pin *i* and plate *j* and operated by the same to raise and lower the piston, as set forth. 110

In testimony that I claim the foregoing as my own I have hereto affixed my signature in 115 presence of two witnesses.

ROBERT HUGHES.
